UNITED STATES PATENT OFFICE

WALTER E. SMITH, OF HINSDALE, ILLINOIS, ASSIGNOR TO AMERICAN BANK NOTE COMPANY, OF NEW YORK, N. Y., A CORPORATION OF NEW YORK

CHECK BOOK

Application filed May 8, 1929. Serial No. 361,281.

My invention relates to check books, and more particularly to a check book including a cover and a replaceable filler, the sheets of which include check forms and stubs, and the binding of which will permit a complete reversal of each of the sheets, so as to facilitate the making out of checks, and the use of the stubs in keeping financial records.

The check book of my invention is adapted for use only with printed sheets having what is called two or more on, since the construction of pocket, or one-on, check books is not such as to permit the utilization of stubs to which the checks are attached, and the size and weight of such pocket check books is so small as to eliminate the conditions present in the larger check books.

The invention further contemplates the production, as an article of manufacture, of a check book in which each of the sheets has two or more on, wherein the printed sheets are carried by a non-flexible base and mounted thereon in a manner to permit a complete reversal of each of the sheets, which base is adapted to be temporarily mounted in a cover.

By this construction, the cover itself may be used with a large number of replacement units, thus avoiding the wastage due to the permanent connection of the cover to a definite number of sheets.

With the above conditions in mind, I have provided a check book containing a hinged cover, and a separable sheet unit, which parts may be so connected as to permit the opening of the cover and the free turning of the sheets without disturbing the relation of the cover and the sheet unit, the manner of connecting the two being such that while the book is in use, there can be no accidental separation of the cover and the sheet unit.

In the book of my invention, the various sheets are so assembled in the sheet unit as to be permanently associated with each other, while permitting the stub sections from which checks have been detached, to be moved away from full sheets, those containing unused checks, and laid flat upon the front cover without turning or buckling such full sheets,

and permitting such full sheets to continue to lie perfectly flat upon the back cover.

The manner of connecting the superimposed sheets of the sheet unit is such as to facilitate the assembly of this unit and secure a sufficient degree of permanency therein to preclude the possibility of the removal of a sheet except as a result of the mutilation thereof.

While the sheet unit is positioned in relation to the cover by means of a tongue thereon co-operating with a pocket formed within the back board of the cover, I supplement this means of connection by interlocking members carried by the back board and the sheet unit preventing the accidental withdrawal of the tongue upon the latter from the pocket in the former.

The various devices employed for associating the sheets and for securing them to the cover are so constructed and assembled in the sheet unit structure, as to not only avoid injury to the cover, but to be so inclosed by the cover as to protect a desk upon which the book is laid.

The construction of the check book of my invention not only has the advantage that the cover may be used with a large number of refill check units, thus effecting a saving to distributors of such books because of the relatively lower cost of the refills than of completely bound books, but the covers may be made in large quantities in anticipation of the need for same, which will permit of quantity production, and corresponding saving, and the sheet units may be printed and assembled as required, by labor unskilled in the book binding art.

While a check book embodying the invention, as a complete unit, is relatively more costly than permanently bound books, the sheet unit itself can be produced at a very much lower cost than a permanently bound book, so that the use of a number of such units with the same cover will be very much less costly than the same number of permanently bound books. Furthermore, this result can be secured and still enable a bank to furnish a better grade, more durable, cover

than is permissible with permanently bound books.

The invention consists primarily in a check book embodying therein a cover comprising a back strip having front and back boards hingedly connected therewith, a sheet unit having a non-flexible base, spaced rigid loop members permanently secured to said base, a plurality of collated sheets having openings therethrough slidably mounted upon said loop members, and means detachably connecting said base with said back cover board; and in such other novel features of construction and combination of parts as are hereinabove set forth and described, and more particularly pointed out in the claims hereto appended.

Referring to the drawings,

Fig. 1 is a condensed view of an open check book embodying the invention, the folded position of one of the stubs being indicated in dotted lines;

Fig. 2 is an enlarged sectional view upon the line 2—2 of Fig. 1 with the sheets removed;

Fig. 3 is a view showing a condensed fragmentary portion of the book proper, with the sheets of the unit removed;

Fig. 4 is an enlarged sectional view on the line 4—4 of Fig. 3; and

Fig. 5 is a detail view of the loop mechanism alone.

Like letters refer to like parts throughout the several views.

In the embodiment of the invention shown in the drawings, I form the cover of a back strip *a*, a front board *b* and a back board *c*, these parts being hinged together so as to permit them all to be positioned in the same plane when the book is open.

The back board *c* is provided with a pocket forming sheet *d*, adjacent but spaced from the back strip *a*, and between this pocket and the back strip said back board has secured thereto a reinforcing strip *e*, carrying one member *f* of a snap fastener. Of course a plurality of such fasteners can be used if desired, but, as will more fully appear hereinafter, one is sufficient to secure the desired result.

This cover may be made of any desired material, either flexible or rigid, and may be decorated or lettered as desired.

Detachably secured within said cover is a sheet unit consisting of a plurality of collated sheets *g*, each of which includes two or more check forms detachably connected with a stub common to all such forms, said sheets being mounted upon a base, formed of superimposed plies *h* and *h'* of cardboard or other suitable material by means of a plurality of loop members to be hereinafter described. Each of the sheets *g* is provided with openings *g'* corresponding in number with, and adapted to receive the loop mem-

bers above referred to. The lowermost ply *h'* is provided with a projecting tongue *h2*, having parallel sides adjacent the ply *h*, adapted to have a fairly close fit with the sides of the pocket formed by the sheet *d*.

Carried by the plies *h*—*h'* is the other member *f'* of a snap fastener, so that when the tongue *h2* is inserted in the pocket within the back board, the snap fastener members may be so engaged as to not only prevent any possible escape of the tongue *h2* from the pocket, but any movement of the base of the sheet unit with relation to the cover.

It will be noted that the snap fastener member *f* is positioned between the reinforcing strip *e* and the back board proper *c*, so that no metal is exposed exteriorly of the cover.

Two superimposed plies *h*—*h'* are used to facilitate the mounting of the loops upon the base formed of such plies.

Said loop members each comprise two headed hollow rivets *j*—*j'*, the heads of which are positioned between the plies *h* and *h'* at suitable spaced distances from each other, and from the snap fastener member *f'*, and at opposite sides of the latter. These rivets are of a length substantially equaling the thickness of the pile of collated sheets, so that in assembling the sheets in relation to the base, said rivets will pass substantially through the openings *g'* in all of said sheets.

Seated in each pair of rivets *j*—*j'* are the opposite legs of a U-shaped loop member *k*, which may be either of tubular metal stock or ordinary round wire.

While the wire loops *k* may be of a gauge to have a close driving fit within the rivets *j*—*j'*, to ensure permanency in the connection between said loops and said rivets, I preferably crimp the rivets firmly upon the loops, as shown more particularly in Figs. 2, 4 and 5 of the drawings. It is not the purpose of these loops to permit the removal or addition of sheets *g*, the sheet unit being a permanent structure when once assembled.

In order to permit the crimping of the rivets *j*—*j'* upon the loops *k*, it is necessary to slide substantially all of the sheets about the loops *k* to upon the rivet *j'*, to permit access to the rivet *j* for crimping purposes, the rivet *j'* preferably being crimped prior to this movement of the sheets.

In the accompanying drawings, *m* indicates the covering material for the front and back boards *b* and *c*, which also form the hinge sections between said boards and the back strip *a*, the edge of said material also forming edge binding securing the pocket forming sheet *d* in position upon the back board *b*.

The manner of use of a book embodying the invention is substantially as follows:

The cover structure and the sheet units

are manufactured separately, the back strip *a* being of sufficient width to accommodate the loop members *k* which project above the pile of sheets slidably mounted thereon.

- 5 The tongue *h2* of the base *h*—*h'* is inserted in the pocket formed by the sheet *d*, the pile of sheets being positioned without this pocket. When the base is so positioned, the side edges of the tongue *h2* have a tight fit 10 with the side edges of the pocket. The base having been properly positioned, the snap fastener member *f'*, or each of said fasteners if more than one be used, is engaged with the snap member *f* carried by the back board 15 *c*. This not only positions the pile of sheets away from the back strip *a* so that the loops *k* will not interfere with the said back strip, but prevents the escape of the sheet unit while in use, and avoids tearing of the pocket. 20 The double hinge connection between the back strip *a* and the front and back boards *b* and *c* permits the front board and the back strip to lie in the same plane as the back board, so that the stubs may be turned upon 25 the loops and upon the rivets *j'*, and laid flat upon the front cover board, and the unused sheets remain flat upon the back cover board. This permits free access to every portion of the back of the stub portion of each 30 sheet turned upon the front cover and the back strip. As a consequence, both hands may be used when filling in the stub portion of a sheet and a check form section attached thereto, and there is no possibility of 35 movement of the sheet while writing thereon. This is also true as to the stub portion of the checks lying upon the front cover board.

When all of the sheets have been used, it 40 is merely necessary to disconnect the members *f*—*f'* of the snap fastener and remove the base *h*—*h'* by slipping the tongue *h2* thereof from within the pocket *d*.

The loop members *k* may be made of tubular or solid stock, as desired. The tubular rivets *j*—*j'*, when crimped upon the loop members, impart the desired permanency of union between these parts, irrespective of whether the loops are solid or tubular. The 50 rivets *j*—*j'* are made of thin metal stock.

The plies *h*—*h'* preferably are glued together, the head of the rivets *j*—*j'* being seated between these plies and secured in position when the plies are connected. The snap 55 fastener member *f'* is not relied upon to connect said plies *h*—*h'*, although it aids in this respect.

It will be noted that the base *h*—*h'* forms a 60 strong support for the rivets *j*—*j'*, and that the manner of mounting these rivets is such that there is little or no possibility of their being torn from the base, or mutilating the cover in any way. It will also be noted that no metal is exposed exteriorly of the cover, 65 thus precluding any possibility of the scratch-

ing of a desk while the check book is in use.

To produce check books having a different number of sheets, it is merely necessary to use loops *k* of different heights, and to use, in the cover proper, back strips of different widths. 70

It is not my intention to claim broadly the use of loop members upon which the check sheets are slidably mounted, as this is old in the arts. 75

The specific details of construction herein described, however, are particularly desirable in the production of a high class check book, the cover of which may be used with a number of refills, the stub portions of the sheets being removable from the cover with the means connecting these sheets, so that the user of such check books is required merely to mount a complete refill unit in the cover, as distinguished from the mounting of such sheets in a binding mechanism forming a permanent part of the cover. 80

It is not my intention, however, to limit the invention to all of the details shown in the accompanying drawings, it being apparent that such are subject to variation while still preserving all of the characteristics of the invention herein described. 90

Having described the invention, what I claim as new and desire to have protected by Letters Patent, is:— 95

1. A check book embodying therein a cover comprising a back strip having front and back boards hingedly connected therewith, a sheet unit having a non-flexible base, spaced rigid loop members permanently secured to said base, a plurality of collated sheets having openings therethrough slidably mounted upon said loop members, and means detachably connecting said base with said back cover board. 100

2. A check book embodying therein a cover comprising a back strip having front and back boards hingedly connected therewith, a sheet unit having a base formed of a plurality of superimposed plies of material, a plurality of pairs of headed hollow rivets, the heads of which are positioned between said plies, a rigid loop member permanently connected with each pair of rivets, a plurality of collated sheets having openings therethrough slidably mounted upon said loop members, and means detachably connecting said base with said back cover board. 110

3. A check book embodying therein a cover comprising a back strip having front and back boards hingedly connected therewith, a sheet unit having a non-flexible base, spaced rigid loop members permanently secured to said base, a plurality of collated sheets having openings therethrough slidably mounted upon said loop members, pocket forming means upon said back board, and co-operating snap fastener members upon said back board and upon said base respectively, where- 120

by said base may be detachably connected with said back board, said base having a tongue thereon entering said pocket.

4. A check book embodying therein a cover comprising a back strip having front and back boards hingedly connected therewith, a sheet unit having a base formed of a plurality of superimposed plies of material, a plurality of pairs of headed hollow rivets, the heads of which are positioned between said plies, a rigid loop member permanently connected with each pair of rivets, a plurality of collated sheets having openings therethrough slidably mounted upon said 15 loop members, pocket forming means upon said back board, and co-operating snap fastener members upon said back board and upon said base respectively, whereby said base may be detachably connected with said 20 back board, said base having a tongue thereon entering said pocket.

In witness whereof I have hereunto affixed my signature, this 4th day of May, 1929.

WALTER E. SMITH.
